UNITED STATES PATENT OFFICE.

CHESTER C. SMALL, DECEASED, LATE OF NEWTON HIGHLANDS, MASSACHUSETTS;
BY JENNIE M. SMALL, ADMINISTRATRIX, OF NEWTON HIGHLANDS, MASSA-
CHUSETTS, ASSIGNOR TO UNITED SHOE MACHINERY CORPORATION, OF PATER-
SON, NEW JERSEY, A CORPORATION OF NEW JERSEY.

MACHINE FOR OPERATING UPON SOLE-LEATHER BLANKS.

Application filed September 16, 1918. Serial No. 254,286.

To all whom it may concern:

Be it known that CHESTER C. SMALL, late of Newton Highlands, in the county of Middlesex and State of Massachusetts, de-
ceased, invented certain Improvements in
Machines for Operating Upon Sole-Leather
Blanks, of which the following description,
in connection with the accompanying draw-
ings, is a specification, like reference char-
acters on the drawings indicating like parts
in the several figures.

This invention relates to machines for
operating upon sole leather blanks and, more
particularly, to a machine for improving
the quality and physical characteristics of
such blanks by the application of pressure
thereto.

It has been known for some time that the
wearing qualities, appearance, and uniform-
ity of conformation of sole leather blanks,
such, for example, as heel lifts, shoe soles,
and the like, were greatly improved by sub-
jecting them to compression or condensation
under heavy pressure. In pursuance of this
knowledge, it has been common practice in
the past to pass pieces of sole leather through
machines in which the leather was subjected
to heavy pressure by co-operating rolls, but
this method of treatment has always been
open to the objection that the thickness of
the leather was appreciably reduced by roll-
ing. This objection is a serious one from
the commercial standpoint, inasmuch as the
market value of a shoe sole or a top lift is
dependent, in a very large degree, upon its
thickness. With increasing scarcity and
demand for sole leather, this consideration
has become of even more importance than in
the past.

Another type of machine for improving
sole leather has been developed, in which
the blank being treated is confined against
lateral expansion by a mold comprising dies
which engage and hold the edges of the
blank while other dies are actuated to ex-
ert very great pressure upon the faces of
the blank. By properly forming the dies, it
has been possible to overcome the objection
of decreasing the thickness of the edges of
the blank, and the product of machines of
this type has been very satisfactory. Inas-
much, however, as the machine must exert its

pressure over the entire area of the blank at
one time, it must have very great strength,
and such machines are ponderous, expen-
sive, and comparatively slow in operation.

The object of the present invention is to
produce a machine for performing an im-
proving operation upon sole leather blanks
which shall be comparatively light, rapid, 60
and simple in construction and operation
and yet shall produce work of the highest
quality, free from the objections above
pointed out.

In pursuance of this object an important 65
feature of the invention consists in the pro-
vision, in combination, with means for con-
fining a blank against lateral expansion, of
means operating progressively across a blank
from one boundary to the opposite boundary 70
thereof to apply pressure to its entire face.
By applying the face pressure at any given
time to a limited area of the blank, the
strength and power required in the machine
are greatly reduced, and it is possible by 75
moving this limited area progressively
across the blank to give a very heavy com-
pression to the entire blank without the
expenditure of a great amount of power.
In a convenient construction for securing 80
this result, the face pressure upon the blank
may be exerted by a roll which may be
moved progressively across the face of the
blank while the latter is held in a blank 85
edge confining mold or, conversely, the mold
containing the blank may be moved past
the roll. A further improvement in the
blank may be secured by subjecting it to a
plurality of pressures, and this may be 90
conveniently effected, without loss of time
or reduction in the product of the machine,
by the provision of a plurality of rolls ar-
ranged to act upon the blank successively
in a single cycle of operation of the machine.
In one practical embodiment of the inven-
tion, the rolls are mounted for free rotation 95
about stationary axes, and the mold contain-
ing the blank is reciprocated past the roll
in such a manner that with two rolls, four
separate applications of pressure upon the 100
blank are secured.

A further feature of the invention con-
sists in the provision of means for confin-
ing separately a plurality of individual

blanks in combination with means for simultaneously exerting pressure upon the faces of all the blanks. By thus operating simultaneously upon a plurality of blanks, it becomes possible to increase greatly the production of the machine. It is preferred so to arrange the blank confining molds that the same pressure is transmitted through all the blanks in series, with the substantial advantage that no more pressure or power is required to treat a plurality of blanks than if a single blank were being operated upon. This result may be secured by mounting the blank confining molds approximately in register with each other upon the substantially parallel opposite faces of a floating mold support arranged to pass between opposed rolls acting to exert pressure upon and transmit pressure to the blanks in series, that is to say, the same application of pressure being transmitted through, and effective upon, all the blanks.

In another aspect, the invention relates to a yieldingly mounted edge mold arranged to permit the application of pressure to the face of a blank confined therein by a pressure applying member overlapping and bearing upon the face of the mold. By the provision of a yielding mounting for the mold, the blank contained therein is subjected to pressure regardless of its thickness, the mold yielding to permit the pressure to be applied directly to the blank while confining its edges effectively against lateral expansion. In this connection the mold is preferably sectional and expansible to permit the blank to be inserted easily, means being provided for contracting the mold upon the blank to hold the latter against expansion during the subsequent application of pressure to the face of the blank, and still another feature of the invention relates to the provision of means for depressing or retracting one section of the mold—in the specific embodiment of the invention hereinafter described, simultaneously with its expansion or opening movement—to permit the compressed blank to be discharged edgewise. In a convenient construction in which the mold is disposed to support the blank in vertical plane, this improved construction permits the blank to be discharged by gravity after it has been operated upon, with a consequent elimination of the usually complicated blank ejecting mechanism.

Other features and advantages of the invention will become apparent in reading the following detailed description of one illustrative embodiment thereof in connection with the accompanying drawings in which:

Fig. 1 is a view in side elevation of a machine embodying the invention; and

Fig. 2 is a view partly in elevation and partly in section on the line 2, 2 of Fig. 1,

Referring now to the drawings, 10 indicates a suitable base, upon which is mounted the main frame 12 of the machine. The driving shaft 14 is journaled in bearings 16 in the frame 12 and is provided with a pinion 18 meshing with a gear 20 upon the crank shaft 22. A crank 24 keyed on the crank shaft actuates a connecting rod 26 connected at 28 to a mold support 30 which is slotted at 32 and is mounted to slide longitudinally of the frame 12 upon gibs 34 bolted to an overhead guide member 36. The slots 32 are sufficiently deep to permit a substantial amount of side movement of the mold support 30 which thus in effect is mounted to "float" for a purpose to be described hereinafter.

Upon opposite faces of the mold support 30 are secured plates 38 of the identical size and shape of the blanks to be produced. In the illustrative embodiment of the invention herein shown and described, these blanks are soles for boots or shoes. The sole shaped plates 38 are surrounded by sectional, blank edge engaging molds, each of which comprises an upper edge die 40 and a lower edge die 42. Interposed between the die 40 and the mold support 30 are springs 43 which tend to hold the die 40 in engagement with the head of the bolt 44 and spaced somewhat away from the face of the mold support. By virtue of this yielding mounting, the edge die 40 is permitted to yield when pressure is applied to the blank 46 confined in the mold by a pressure roll 48, which extends across the blank and overlaps the face of the die.

The other mold section or die 42 has a corresponding yielding mounting in a slide 50, guided for movement in the direction of the depth of the mold by a T slot connection and guide 52. The slide 50 is wedge shaped and abuts against a corresponding inclined surface 54 formed upon the mold support 30. The two slide members 50 shown at opposite sides of the supporting member 30 are connected by a pull spring 56 which always tends to draw the slide members toward each other and into firm engagement with the inclined faces 54. The T shaped cross bar 52 is carried by the upper ends of a pair of toggles 58, 60, the lower ends of which are stepped in a cross bar 62 supported at the lower end of a vertical bar 64 secured in the mold support 30 by a key 66. A similar toggle and supporting arrangement 68 is provided at the other end of the mold and the centers of the toggles 58, 68 are connected by a bar 70 which is normally drawn toward the left, see Fig. 1, by a pull spring 72 connected at one end to the bar 70 and at the other end to a lug 74 projecting downwardly from the mold support 30. In the position of the parts when the spring 72 is permitted to operate

100

130

upon the bar 70, the toggles 58, 68 are straightened and the expansible edge mold comprising the dies 40, 42 is closed upon the periphery of the blank, as illustrated in Fig. 2. In the upward movement of the slide members 50, produced by the straightening of the toggles, the said slide members move along the inclined faces 54 until at the end of such upward movement, their outer faces 10 are flush with the corresponding opposite faces of the member 30, and the dies 42 are flush with the dies 40, forming two parallel, opposite, outwardly facing blank confining molds substantially in register with each other. 15 A stop screw 76 adjustably threaded into the frame 12 is positioned to be engaged by the end of the bar 70 when the latter is moved to the left hand limit of its path. 20 By this means the toggles 58, 68 are broken, drawing the slides 50 downward along the inclined faces 54. The sectional mold is thus expanded to relieve the blank from edge pressure and simultaneously the lower dies 42 are retracted or depressed until their outer faces are flush with, or below the faces of, the bottom plates 38 of the molds. 25 With the parts in this position the sole blanks contained in the molds are free to be discharged edgewise by gravity, leaving the molds empty for the reception of fresh blanks to be operated upon. Shelves 78 are provided, one on each side of the mold supporting structure, to contain the supply of 30 blanks to be treated.

Two pairs of freely revoluble rolls 80, 82 are journaled in roll carriers 84 and are simultaneously adjustable toward and from each other by wedges 86 interposed between 35 the roll carriers and the upstanding portions of the frame which support the overhead guide member 36. The wedges 86 are actuated by screws 88 connected by miter gears 90 to a common shaft 92 provided 40 with a hand wheel 94 for rotating the shaft to effect the desired adjustment. By this means, the space between the rolls may 45 readily be adjusted to secure the desired pressure in accordance with the thickness 50 of the stock being operated upon.

The actuation of the machine may be controlled by any usual or suitable form of one revolution clutch 96 serving to connect and disconnect the driving pulley to and from 55 the shaft 14.

The operation of the machine is as follows: Assuming the parts to be in the position illustrated in Fig. 1, the operative picks up soles from the shelves 78, one on 60 each side of the machine, and inserts them in the corresponding molds. The machine is now started, and, as the bar 70 leaves the stop screw 76, the spring 72 causes the toggles 58, 68 to be straightened, and the sectional edge molds to be contracted upon the

edges of the blanks to hold them against lateral expansion. As the mold structure continues to be moved toward the right by the connecting rod 26 which is actuated by the crank on the shaft 22 it causes the molds 70 with the blanks contained therein to be drawn between the pairs of pressure rolls 80, 82 in succession. The floating mounting of the mold support 30 permits sidewise motion of the molds and blanks to equalize 75 the pressure upon the two blanks, with the result that the same pressure is transmitted simultaneously through both blanks in series and its total amount need be no greater than that required for a single blank. As 80 the mold structure advances, the rolls 80 act progressively to apply pressure to the faces of the blanks over a limited area extending across the blank and moving from one boundary to the other as the latter advances between the rolls. 85 After passing the rolls 80, the blanks are acted upon by the rolls 82, which effect a second application of pressure upon the faces of the blanks, and as the crank shaft 90 completes its revolution, the blanks are returned between the two pairs of rolls in succession to the starting position; consequently, each blank in the single cycle of 95 the machine has been subjected to four distinct applications of pressure.

As the mold structure reaches its initial position, the bar 70 engages the stop screw 76, the toggles 58, 68 are broken with the consequent opening of the side dies and 100 depression or retraction of the lower dies, permitting the treated blanks to fall out of the molds which are now ready for the reception of the next pair of blanks.

The machine may be operated a cycle at 105 a time, as described, or, when an operative has become sufficiently practiced, the treadle may be held depressed and the machine operated continuously, the fresh blanks being fed to the molds each time they reach 110 feeding position.

It should be understood that a machine designed for operating upon sole blanks has 115 been selected and described in detail only for the purpose of affording an illustration of one embodiment of the invention and that the invention is equally applicable to machines for operating upon sole leather blanks of other shapes and descriptions. It will be apparent that the invention provides a machine for performing an improving operation upon sole leather blanks, which is comparatively light and simple in construction and operation, and is capable of large production of work of a high 120 quality with a minimum expenditure of power.

Having described the invention, what is claimed as new and desired to be secured by Letters Patent of the United States is:— 125

1. In a machine for operating upon sole leather blanks, the combination of means for holding an isolated blank while flat and confining it against lateral expansion, and means operating progressively from one boundary of the blank to the opposite boundary thereof to exert pressure upon the entire face of the blank.
2. In a machine for operating upon sole leather blanks, the combination of means for holding an isolated blank while flat and confining it against lateral expansion, and means for exerting pressure upon a limited area of the face of the blank operating progressively from one edge to the opposite edge of the blank so as to cover the entire face of the blank.
3. In a machine for operating upon sole leather blanks, the combination of means for holding an isolated blank while flat and confining it against lateral expansion, and means movable in a straight path for exerting a rolling pressure progressively across the face of the blank.
4. In a machine for operating upon sole leather blanks, the combination of means for confining a blank while flat against lateral expansion, and a plurality of means for exerting successive rolling pressures upon the entire blank progressively from one boundary to the opposite boundary thereof.
5. In a machine for operating upon sole leather blanks, the combination of means for engaging the entire edge of a blank while flat and confining it against lateral expansion, and means for exerting a plurality of successive rolling pressures upon and across the face of the blank.
6. In a machine for operating upon sole leather blanks, the combination of means for confining a blank while flat against lateral expansion, and a plurality of means movable through straight paths and operating in succession to exert pressure upon the face of the blank from one boundary to the other.
7. In a machine for operating upon sole leather blanks, the combination of means for confining a blank while flat against lateral expansion, and a plurality of means operating in succession to exert a plurality of rolling pressures upon the face of the blank and across the blank from one boundary to the other.
8. In a machine for operating upon sole leather blanks, the combination of means for engaging the entire edges of a plurality of individual blanks and confining them against lateral expansion, and means for simultaneously exerting rolling pressure upon the faces of said blanks.
9. In a machine for operating upon sole leather blanks, the combination of means for confining a plurality of individual blanks against lateral expansion, and means for exerting progressively moving pressure simultaneously upon the faces of said blanks in series.
10. In a machine for operating upon sole leather blanks, the combination of means for confining a plurality of individual blanks against lateral expansion in substantially parallel relation, and means for exerting the same progressively moving pressure simultaneously upon all of said blanks.
11. In a machine for operating upon sole leather blanks, the combination of means for confining a plurality of individual blanks against lateral expansion substantially in register with each other, and means for exerting the same progressively moving pressure upon, and transmitting it through, all of said blanks.
12. In a machine for operating upon sole leather blanks, the combination of means for supporting a plurality of blanks with their faces in parallel, spaced relation, and means for simultaneously exerting progressively moving pressure upon the opposite outer faces of said blanks.
13. In a machine for operating upon sole leather blanks, the combination of means for confining a plurality of individual blanks against lateral expansion and supporting them with their faces in parallel spaced relation, and means for simultaneously exerting moving pressure upon the faces of said blanks while they are maintained in such relation.
14. In a machine of the class described, the combination of a blank edge confining mold, to hold a blank while it is flat, a pressure roll for exerting pressure upon the face of a blank in the mold, and means for producing relative movement between the roll and the mold to cause pressure to be exerted progressively in a right line along the face of the blank.
15. In a machine of the class described, the combination of a mold support, blank edge confining molds facing outwardly on opposite sides of said support, and means for exerting pressure simultaneously upon the faces of blanks confined in said molds.
16. In a machine for the class described, the combination of a floating mold support, molds facing outwardly upon opposite sides of said support, pressure rolls mounted to bear upon the faces of the molds, and means for causing relative progressive movement to the rolls across the molds.
17. In a machine of the class described, the combination of a floating mold support, molds facing outwardly upon opposite sides of said support, pressure rolls bearing upon the faces of the molds, and means for moving the mold support between the rolls.
18. In a machine of the class described, the combination of a floating mold support,

5 molds facing outwardly on opposite sides of said support, a plurality of pairs of pressure rolls spaced apart to bear upon the faces of the molds, and means for reciprocating the 5 mold support between said pairs of pressure rolls in succession to cause the rolls to act successively upon blanks confined in the molds.

19. In a machine of the class described, 10 the combination of a support for one face of a blank, a blank edge confining mold mounted upon said support to yield toward the latter, and means for progressively exerting pressure upon the opposite face of a blank 15 confined in the mold.

20. In a machine of the class described, 20 the combination of a mold support, a sectional edge mold mounted upon the support, and means for exerting pressure upon a blank confined in the mold, one section of the mold being depressible to permit the blank to be discharged from the mold after the pressure applying operation.

21. In a machine of the class described, 25 the combination of a mold support, a sectional blank edge confining mold upon said support, means for exerting pressure upon the face of a blank confined in the mold, and means for depressing a section of the mold 30 to permit the blank to be discharged edge-wise therefrom.

22. In a machine of the class described, 35 the combination of a mold support, a sectional blank edge confining mold arranged upon the support to confine a blank in vertical position, and means for retracting a section of the edge mold to permit a blank to drop away from the mold.

23. In a machine of the class described, 40 the combination of a sectional, contractile mold, means for contracting the mold upon the edges of a blank, and means for simultaneously expanding the mold and depressing a section thereof to permit a blank to be discharged edgewise from the mold.

24. In a machine of the class described, 45 a mold having mutually perpendicular surfaces to support the edges and one face of a blank, means to apply pressure to a surface 50 narrower than the width of the blank, and mechanism to reciprocate said mold past

said means progressively to compress a blank therein.

25. In a machine of the class described, in combination, a support for a plurality of 55 blanks in parallel relation, and means to exert oppositely-directed balancing pressures progressively along opposite faces of different blanks.

26. In a machine of the class described, in combination, a support for the edges and one face of a blank, means progressively operating along one face of a blank supported thereby to compress the blank, and means for manually controlling the pressure on the 65 blank.

27. In a machine of the class described, in combination, a pair of parallel pressure rolls, a work-support in the space between the rolls, and means relatively bodily to 70 move the rolls and the work-support in such a manner that pressure on the work by one roll is balanced by the pressure of the other roll.

28. In a machine of the class described, in 75 combination, a pair of parallel pressure rolls, a work-support interposed between the opposed faces of the rolls, means relatively to reciprocate the rolls and the work-support, and means simultaneously to adjust the rolls 80 toward and from the work-support.

29. In a machine of the class described, in combination, a peripheral support to confine the edges of a blank, means to apply pressure to a blank confined thereby progressively along one face of the blank, and 85 manually-operable means to adjust the amount of pressure on the blank.

30. In a machine of the class described, in combination, a peripheral support to confine the edges of a blank, a roll progressively to compress an entire blank confined thereby in moving from one edge to the opposite edge of the blank, and manually-operable means to move the roll toward and 95 from the blank to adjust the pressure.

In testimony whereof I have signed my name to this specification.

JENNIE M. SMALL,
Administratrix of the estate of Chester C.
Small, deceased.
